ASSEMBLER GUIDE FOR TYPESETTING MACHINES

George Rupert Schladetzky, Omaha, Nebr.

Application July 13, 1935, Serial No. 31,255

12 Claims. (Cl. 199—28)

This invention relates to the class of type setting machines and pertains particularly to an improved element in a machine of the type known as "Linotype".

5 The primary object of the present invention is to provide an improved assembly mechanism for a type casting machine by means of which the transposition of letters of a word is prevented in the event that the operator of the 10 machine works or operates the same at too great a speed.

In typesetting machines of the character referred to, the assembling of the matrices can only progress at a prescribed rate and if the 15 operator of the machine increases the speed at which he releases the matrices, it frequently happens that a spaceband will be introduced ahead of a matrix forming the last of a word forming group instead of behind the same so that 20 the last letter of the word will be printed in front of the next succeeding word.

The present invention is designed to overcome the foregoing difficulty by moving the matrix from the inclined position which it assumes in 25 approaching the assembler, directly to a vertical position without being retarded by the chute finger so that a released spaceband cannot interpose itself between the last matrix going to make up a word group and the preceding ones.

30 Another object of the invention is to provide an adjustable chute finger which works as an auxiliary to an improved form of the chute finger which at present is employed, whereby the said auxiliary finger may be adjusted relative to the assembler belt in accordance with the thickness of the type font being used.

Still another object of the invention is to provide an improved chute finger which is adapted for forward and rearward movement.

40 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in 45 the appended claims.

In the drawing:

Figure 1 is a view in elevation of the device embodying the present invention, showing the 50 same in working position;

Figure 2 is a vertical sectional view through the central part of the spaceband chute finger;

Figure 3 is a sectional view taken on the line 3—3 of Figure 2;

Figure 4 is a perspective view of the lower part 5 of the chute finger;

Figure 5 is a view in section through the upper part of the auxiliary chute finger and the mounting therefor;

Figure 6 is a view in top plan of the auxiliary 10 chute fingers and mounting for the same;

Figure 7 is a sectional view taken on the line 7—7 of Figure 5;

Figure 1 illustrates a portion of the assembler mechanism of a type casting machine wherein 15 is shown one of the two pulley wheels 1 over which the assembler belt 2 passes. The numerals 3 indicate certain of the chutes nearest the assembler proper through which the matrices pass to the assembler belt while the numeral 4 indicates the spaceband chute through which the 20 spacebands pass to the assembler.

A portion of the assembler structure is designated by the numeral 5, in the lower part of which the assembling elevator 6 is disposed for 25 the reception of the matrices and spacebands which are shifted into the proper position therein by the star-wheel 7. The numeral 8 indicates a guide over which the matrices pass from the assembler belt to the star-wheel and above which 30 the element known as the chute finger is disposed.

The present invention constitutes an improvement in the chute finger at present in use and is indicated as a whole by the numeral 9. This 35 device consists of the plate 10 which is firmly secured to the wall of the machine between the spaceband chute and the matrix chutes in the manner illustrated. At the end of the plate nearest the spaceband chute, there is secured the improved chute finger which is indicated as a 40 whole by the numeral 11 and which comprises three parts in the form of arms which are connected together in end to end relation. The upper arm, which is indicated by the numeral 12, 45 has an edge flange 13 which is secured to the plate 10 and at its lower end a pair of apertured ears 14. These ears are in spaced relation, as shown, and between them are disposed the spaced apertured ears 15 of the intermediate arm 16. 50 The lower corners of these ears 15 are rounded, as indicated at 17, so that the arm 16 may swing in one direction upon the pivot pin 18 which passes through the aligned apertures of the ears 14 and 15. A spring 19 on this pivot pin nor- 55

mally maintains these two arms in parallel relation.

At the lower end of the intermediate arm are the two spaced apertured ears 20 between which are located a similar pair of spaced apertured ears 21 formed integral with the upper end of the lower arm 22. The lower corners of these ears 21 are rounded, as indicated at 23, so that the arm 22 may swing in the opposite direction 5 from the arm 16, upon the pivot pin 24, which passes through the alined openings of the ears 20 and 21. This pin has mounted thereon the coil spring 25 which normally maintains the arm 22 in the desired relation with the upper arms.

10 This arm 22 is normally angularly disposed with respect to the upper and intermediate arms and terminates at its lower end in the spaced tines 26 which extend beneath the spaceband chute 4 and which have their free ends curved 15 downwardly toward the assembling elevator, as indicated at 27. These down-curved tines have their ends extended slightly into the assembler mechanism.

Disposed behind the chute finger 11 is an auxiliary chute finger 28 which is in the form of a 20 relatively long flexible band of material, preferably spring copper. This is attached at its upper end to a yoke 29 which carries spaced ears 30 through which extend a pivot pin 31 which has 25 one end secured in and extending at right angles from the face of the plate 10. This yoke is oscillatable on the pin 31 and has integral with it the short tongue 32 which extends forwardly from the finger 28.

30 Secured to the plate 10 between the yoke 29 and the chute finger 11 is a post 33 which extends outwardly from the plate and which is threaded throughout to receive the interiorly threaded sleeve 34. This sleeve 34 has formed 35 on its inner end the cone 35, the apex of which is directed toward the plate 10 and the surface of which is ribbed longitudinally and contacts with an edge of the tongue 32 across which it moves. By moving this sleeve 34 inwardly to 40 ward the plate 10 or outwardly on the threaded post 33, the cone will move against or away from the tongue 32 and so oscillate the same and the finger 28 which is attached thereto.

45 Adjacent the auxiliary chute finger 28 is a second and shorter auxiliary finger which is secured at one end to the bracket 29 and which is indicated by the numeral 39. This second auxiliary finger extends downwardly in divergent relation with the finger 28 toward the upper part 50 of the matrix guide 8 while the larger auxiliary finger 28 extends down over and in spaced relation with the guide 8, being directed toward the assembling elevator.

55 It will be apparent that the actuation of the adjustment cone 35 will move the two fingers 28 and 39 simultaneously and by this means, the space between the auxiliary finger 28 and the matrix guide surface 8 will be adjusted in accordance with the thickness of the type font used.

60 The form of the star-wheel illustrated in Figure 1 and indicated by the numeral 7 illustrates an improvement in this element which facilitates the passage of the spaceband from its guide into the assembler. These star-wheels have four 65 arms, each of which is indicated by the numeral 36, each of which terminates in a head 37. At the present time, these heads are formed with their outer ends at right angles to the sides or, in other words, have what are known as square 70 ends. The operation of the wheel has been found 75

to be improved by beveling or cutting off the opposite corners of each of the heads, as indicated at 38, so that each head appears as a point instead of square, as previously. With this construction, the spacebands are found to more readily descend to their proper places instead of striking on the end of an arm of the wheel as they frequently do at the present time. 5

In operation, the present improved matrix controlling unit causes the matrices to make only 10 one movement from the 45° angle at which they descend to the straightening up or vertical position which they must assume in entering the assembler. The matrix, therefore, comes directly into the assembler without interference and as 15 it contacts the star-wheel, which forces it to the vertical position, it continues to move without interference to its upper end and only touches the downwardly curving points 27 of the tines 26 of the chute finger. This contact of the upper 20 end of the matrix with the downturned points of the tines 26 does not take place, however, until after the top of the matrix has passed the point where the spacebands descend. With the present chute fingers, when the star-wheel comes in 25 contact with the matrix, it causes the matrix to force the chute finger to move against the spring tension which holds it, before the matrix starts to come to its vertical position, thereby causing a slowing up of the progress of the matrix 30 and allowing time for the spaceband to descend and enter between the matrix and those which have preceded it instead of entering behind the matrix as it should do. With the present device, the auxiliary chute finger holds the 35 matrix flat against the guide surface until it is engaged by the star-wheel and its upper end is then quickly moved over to vertical position and into contact with the downturned ends 27 of the tines 26, as previously described so that there is 40 no slowing up of its movement from the angular to the vertical position and the spacebands are not given time to fall into the wrong position.

45 By forming the guide finger or spaceband guide 11 with the double hinge, means is provided whereby the operator may readily insert special characters into the assembler by hand and in addition by disposing the tines at the lower end of the chute finger with the curved 50 points slightly inside the assembler, the spacebands as they descend are kept in a vertical position until the star-wheel pulls them down to their proper places, thus doing away with the leaning of the bands which necessitates the operator pushing them down by hand before sending the matrix line to the mold.

55 What is claimed is:—

1. In a type setting machine including an assembler, an assembler belt, a spaceband chute and matrix chutes, a chute finger having a long 60 portion secured at one end adjacent the spaceband chute, tines projecting from the other end of said long portions across the discharge end of the spaceband chute, said tines being resiliently maintained in position relative to said last chute, 65 an auxiliary resilient chute finger disposed between the first chute finger and the assembler belt and maintained spaced from the latter, and means for adjusting said auxiliary chute finger relative to the assembler belt and independently 70 of the first chute finger.

2. In a type setting machine including an assembler, an assembler belt, a spaceband chute and matrix chutes, a chute finger comprising an elongated portion secured at one end between the 75

matrix chutes and the spaceband chute, tines projecting from the other end of said portion and extending across the discharge end of the spaceband chute, and a joint in said finger permitting 5 the swinging movement of said tines in two directions from a normal operating position between the spaceband chute and the assembler belt.

3. In a type setting machine including an assembler, an assembler belt, a spaceband chute and matrix chutes, a chute finger comprising a double jointed arm portion secured at one end adjacent the spaceband chute and tines projecting in spaced relation from the other end 10 of the arm portion across the discharge end of the spaceband chute, resilient means maintaining said double joints in a normal operating position, and an elongated resilient auxiliary chute finger secured at one end between the spaceband 15 chute and the matrix chutes and extending downwardly between the assembler belt and the lower end of the first mentioned finger.

4. In a type setting machine including an assembler, an assembler belt, a spaceband chute and matrix chutes, a chute finger comprising a double jointed arm portion secured at one end adjacent the spaceband chute, tines projecting in spaced relation from the other end of the arm portion across the discharge end of the 20 spaceband chute, resilient means maintaining said double joints in a normal operating position, and an elongated resilient auxiliary chute finger secured at one end between the spaceband chute and the matrix chutes and extending downwardly 25 between the assembler belt and the lower end of the first mentioned finger, said tines having their free ends extended slightly into the assembler and curving downwardly into the same.

5. In a type setting machine including an assembler, an assembler belt, a spaceband chute and matrix chutes, a chute finger comprising an elongated portion made up of an upper, an intermediate and a lower arm, pivotal means connecting the intermediate arm at its ends with the 30 upper and lower arms, the pivotal means at the upper end of the intermediate arm permitting the swinging movement of the same in one direction only, the pivotal means at the lower end of the intermediate arm permitting the 35 swinging movement of the lower end in the opposite direction only, resilient means normally maintaining said arms in a predetermined relation, and tines formed integral with the lower end of said lower arm and extending across the 40 lower end of the spaceband chute.

6. In a type setting machine including an assembler, an assembler belt, a spaceband chute and matrix chutes, a chute finger having an elongated portion secured at one end adjacent the spaceband chute and a pair of tines projecting from its other end across the discharge 45 end of the spaceband chute, said tines being curved downwardly at their free ends, an elongated resilient auxiliary chute finger pivotally secured at one end adjacent the secured end of the first mentioned finger and extending downwardly between the lower end of the first mentioned finger and the assembler belt, and adjustable means at the upper end of the auxiliary chute finger for effecting the oscillation of the 50 same.

7. In a type setting machine including an assembler, an assembler belt, a spaceband chute and matrix chutes, a chute finger having an elongated portion secured at one end adjacent

the spaceband chute and a pair of tines projecting from its other end across the discharge end of the spaceband chute, said tines being curved downwardly at their free ends, an elongated resilient auxiliary chute finger pivotally secured 5 at one end adjacent the secured end of the first mentioned finger and extending downwardly between the lower end of the first mentioned finger and the assembler belt, adjustable means at the upper end of the auxiliary chute finger 10 for effecting the oscillation of the same, and a second auxiliary chute finger secured to the pivotally attached upper end of the first mentioned auxiliary finger and extending downwardly in divergent relation with the same and swingable 15 therewith.

8. In a type setting machine including an assembler, an assembler belt, a spaceband chute and matrix chutes, a chute finger comprising a double jointed arm portion secured at one end adjacent 20 the spaceband chute, tines projecting in spaced relation from the other end of the arm portion across the discharge end of the spaceband chute, and resilient means maintaining said double joints in a prescribed normal position. 25

9. In a type setting machine including an assembler, an assembler belt, a spaceband chute and matrix chutes, a body oscillatably attached to the machine between the spaceband and matrix chutes, an elongated resilient auxiliary 30 finger secured at one end to said body and extending downwardly into relatively close proximity to the assembler belt and extending in the direction of movement of the assembler belt, and means for effecting the oscillation of said body 35 whereby the free end of the auxiliary chute finger may be adjusted relative to the assembler belt.

10. In a type setting machine including an assembler, an assembler belt, a spaceband chute and matrix chutes, a body oscillatably attached to the machine between the spaceband and matrix chutes, a resilient auxiliary finger secured at one end to the body and directed downwardly toward the assembler belt, a second resilient auxiliary finger secured at one end to the body and directed downwardly toward the assembler belt and forwardly in the direction of travel of the belt and terminating at its free end in relatively close proximity to the belt, resilient 45 means normally maintaining the oscillatable body in one position, and shiftable means in engagement with the body for effecting the oscillation of the latter and the adjustment of the position of said fingers relative to the belt. 50

11. In a type setting machine including an assembler, an assembler belt, a spaceband chute and matrix chutes, a body oscillatably mounted upon the machine between the spaceband and matrix chutes, an arm secured to the body, an elongated resilient auxiliary finger secured at one end to the body and extending downwardly toward the assembler belt and forwardly in the direction of movement of the belt and terminating at its free end in relatively close proximity to the belt, resilient means normally maintaining said oscillatable body in one position, a screw mounted at one end to extend across said arm, and a nut threaded upon the screw and having a head of conical formation, the surface of said 60 conical head engaging said arm whereby movement of the nut longitudinally on the screw will effect the oscillation of the body and finger 65 through the arm.

12. In a type setting machine including an as- 70

75

sembler, an assembler belt, a space band chute and matrix chutes, a chute finger disposed between the matrix chutes and the spaceband chute, said finger including two portions, one of said portions being pivotally attached to a fixed support and adapted to swing in one direction only relative to said support, a pivotal connection between the said portions which permits the other portion to swing only in the opposite direction 5 to the first portion, said second portion including a pair of spaced tines projecting across the dis-

charge end of the spaceband chute, resilient means yieldingly holding said portions against movement, and an elongated auxiliary chute finger mounted at one end between the spaceband chute and the matrix chutes and extending downwardly between the assembler belt and the lower part of the said other portion and adapted to yield toward said other portion for the passage of a matrix therebeneath. 10
